VALVE SHIELD

Thomas R. Burke, Chicago, Ill.

Application January 13, 1932. Serial No. 586,419

6 Claims. (Cl. 137—93)

This invention has reference to flushing valves and more particularly to valves of the direct flush type which are connected directly with the water supply and the fixture to be flushed. These flush valves, as now generally made and installed, present outer metallic surfaces of various contours which tarnish and corrode so that they become unsightly and are not easily kept clean and sanitary. The present invention provides a shield or housing or casing which will completely surround the mechanical working unit of the valve in such a manner as to reduce the number of projections which are now usually present and which render cleaning of the valve or fitting exceedingly difficult. The shield of my invention dispenses with the usual outlet of the flushing valve and provides a casing member or section which performs the functions of the outlet so that the number of parts is reduced and the cost of production and installation will be minimized. The invention provides a shield or casing which may be enameled or plated so as to be given any desired color finish and harmonize completely with the fixture to which it is applied and the surroundings of its installation. The invention also provides a casing or shield of such form or design that it may be produced in any desired metal or other material, the exterior finish of which will be permanent and easily cleaned. A further object of the invention is to provide a shield or casing having the stated characteristics which may be very easily applied to the valve and will be firmly supported by the valve. Other objects of the invention will appear incidentally in the course of the following description, and the invention resides in certain novel features which will be particularly pointed out in the appended claims.

In the annexed drawings,

Figure 1 is a perspective view of a flush valve and fixture having my improved shield applied thereto,

Fig. 2 is a vertical section of the shield, the valve being shown in elevation partly broken away,

Fig. 3 is a view, partly in plan and partly in horizontal section, on the line 3—3 of Fig. 2,

Fig. 4 is a perspective view showing parts of the shield separated but in their proper relative positions.

The reference numeral 1 denotes a fixture which is to be flushed and the numeral 2 indicates the flush valve. The flush valve may be of any known or approved type and is illustrated with a lateral inlet nipple 3 which is adapted to be coupled to a lateral nipple or pipe member 4

which extends from the casing 5 of the controlling valve 6 which may be of any well-known type and is to be adjusted so as to regulate the volume of the inflow or to cut off the flow entirely when repairs are to be made. The valve casing 5 is connected to the supply pipe 7 which, in the illustrated installation, is brought through the wall of the room in which the apparatus is installed. A flange or collar 8 is disposed around the basal end of the valve casing 5 and abuts the wall, as shown, so that a neat finish may be attained. The stem 9 of the controlling valve is threaded at its outer extremity to engage in a socket 10 which is swiveled in and extends through the outer end of the valve casing 5 and about which is fitted a gland or packing box 11, all of these parts being of any preferred form. The outer extremity of the swiveled socket 10 is non-circular in cross section so as to be engaged by the boss 12 on the inner side of a cap 13 which is fitted to the valve casing. The cap 13 is semi-spherical throughout the greater portion of its extent while its margin is cylindrical and of a proper diameter to abut the outer end of the valve casing and lie flush therewith so that a smooth surface is provided over the entire exterior of the valve casing and the cap which will lend itself readily to any desired finish. A screw 14 is inserted through the cap into the extremity of the socket 10 so that the cap will be held in position and will constitute a handle for the controlling valve or stop. When the cap or handle is turned, it will impart rotation to the socket and thereby effect longitudinal movement of the stem 9 and the valve 6 to set the valve for any desired opening which may be deemed most desirable. The entire outer surface of the valve casing 5 and its branch pipe member 4, the collar 8 and the cap 13 are given the same finish, which may be an enamel color which will best harmonize with the fittings to which it is applied and the surroundings of the installation.

The pipe member 4 is coupled to the inlet nipple 3 of the flush valve 2 in any approved manner, a coupling collar 14' being illustrated in Fig. 2. The coupling collar is slipped onto the pipe member 4, and a flange 40 is then screwed into the end of the pipe member to provide a shoulder against which the collar abuts, as shown, when drawing the pipe member into close union with the nipple 3. The union of the pipe member and nipple is effected by screwing the collar onto the nipple, as will be understood upon reference to Fig. 2, the flush valve being thereby firmly secured in position. The shield of the present invention includes a lower section 15 which has an upper substan-

tially cylindrical body 16 and a lower pipe section 17 which constitutes the outlet for the flush valve, the lower end of said pipe section 17 being disposed within the upper end of the delivery pipe 18 which extends to the fixture which is to be flushed, a packing box 19 being disposed about the shield so as to prevent leakage and a gasket 20 being arranged around the end of the delivery pipe and against the part which is to be flushed for the same purpose. A smooth surfaced collar 21 is disposed about the lower end of the pipe section 17 and the parts around the same, as clearly shown in Figs. 1 and 2, so that the finish will correspond to the collar 8 which presents the finish for the inlet pipe. The upper end of the shield section 15 is open, as clearly shown in Fig. 4, and at said upper end is formed a lateral semi-cylindrical arm 22 which extends under and about the nipple 3 of the flush valve and, at its outer extremity, is formed with an inturned flange 23 fitting about the pipe member 4 of the controlling valve casing. Just below the horizontal plane of the bottom of the arm 22 an internal annular shelf 24 is provided on the shield member 15 and the flush valve rests on this flange, as clearly shown in Fig. 2, a cushion 25 of rubber or other suitable material being disposed between the shelf and the lower end of the valve to resist possible leakage. A securing screw 26 is inserted through the arm 22, at any convenient point, and engaged in the nipple 3 so that, as the screw is turned home, the shelf will be drawn to the valve which will be firmly seated, it being understood that there is sufficient clearance between the edge of the flange 23 and the bottom of the pipe 4 to accommodate the securing movement. Thus a single fastening screw will serve to secure the valve properly in position within the shield. The flushing valve body 2 might tilt while the screw 26 is being turned home and, therefore, fail to seat properly upon its support. To avoid such action, I provide lugs 41 on the body about one-third its height above the bottom. If three of these lugs be provided 120° apart, two of them will immediately engage the inner surface of the section 15 and prevent tilting of the body. It is also to be noted that the inverted cap on the lower end of the body fits snugly in the section 15 and thus insures straight downward travel of the valve body as it moves to its support. Initially, the outlet member 17 had been dropped loosely in the fixture where it rests while the union coupling at the collar 14 is tested. After the screw 26 is turned and the packing box 19 set, the valve is tested for leakage past the gasket or cushion 25, and the upper member of the shield is set in place after the test is satisfactory. It will be understood, of course, that the collar 21 is loose upon the outlet 17 and may be easily slipped upward to afford access to the packing box and then moved downward to cover the box and adjacent parts.

The flush valve includes a depending stem 27 which is ordinarily operated by the thrust of a handle, such as the handle 28 illustrated in the accompanying drawings, which tilts the stem and said handle has been mounted in the side of a lower extension or elongation of the valve body. Any pressure exerted inwardly through the handle 28 will rock the stem 27 and unseat the primary valve of the flush valve proper so that the desired flow of water will be set up. In the present invention, the operating handle 28 is independent of the flush valve body and is mounted within a box 29 formed on the side 75 of the shield member 15, being carried by a cap

or socket 30 which is threaded into the box, as clearly shown in Fig. 2. An offset 31 is formed on the inner surface of the section 16, immediately under the shelf 24, and suitable packing is placed within this offset, around the plunger 32, so that leakage around the plunger will be prevented. The plunger 32 extends from and may form an elongation of the handle 28 and bears against the valve stem 27, as shown and as will be understood.

The upper portion of the flush valve 2 is enclosed by an upper shield member 33 which is substantially cylindrical in form having an open lower end and an upper closed end of a semi-spherical formation. At the lower end of the member 33 is a lateral arm 34 which is semi-cylindrical in form and, at its outer extremity, is provided with an inwardly projecting flange 35 which fits around the pipe section 4, as shown in Fig. 2 and as will be understood. The lower end of the shield member 33 and the lower edges of the arm 34 mate with and rest on the upper edges of the shield member 15 and the arm 22, as will be understood, so that when the two shield members are brought together about the valve the surfaces of these two members will be flush and cleaning, when necessary, may be very easily accomplished. An opening 36 is formed in the upper end of the shield member 33 and a fastening screw 37 is seated in said opening 105 which is countersunk to accommodate the head of the screw, the end of the screw engaging in the upper end of the flush valve body so that the shield member 33 will be firmly held in place with a single fastening.

From the foregoing description, taken in connection with the accompanying drawings, it will be seen that I have provided an exceedingly simple shield or casing for a flush valve of the direct type which may be very easily fitted about the valve and which will present a pleasing appearance and may be given any desired finish. The parts of the casing are readily brought together in mating or matched relation and the lower member or section of the shield functions as the outlet for the flush valve, thereby eliminating the outlet heretofore provided as an accessory to the mechanical unit of the valve and avoiding the expense of such part. This lower section also is so formed as to accommodate the usual oscillating handle so that the handle may be detached from the operating mechanical unit of the valve and such faults of either part as may develop in use may be separately treated and the faulty part repaired or removed without requiring replacement of the part in which no fault has developed. The lower member of the shield may be so shaped as to be easily fitted around the lower sections of most makes of commercially successful flush valves so that the valves may be furnished without their usual outlet tubes, nozzles, etc., and finished off squarely at the bottom to rest upon the support provided in the lower shield member. A single ordinary screw, applied in the most convenient position, serves 140 to secure each member of the shield about the valve so that the valve is brought into proper position within the shield and security and tightness of the fitting naturally results.

The outlet member 17 forms a stable or fixed member of the entire assembly and is especially useful in positioning the flush valve handle independently of the flush valve proper. It may easily house a vacuum breaker which is frequently furnished in connection with flush valves to 150

prevent reversal of flow or the siphoning of the contents of the fixture back into the water-supply system, the outlet being of ample capacity to receive the vacuum-breaker without retarding the flow.

Having thus described the invention, I claim:

1. The combination with a flush valve including a casing having laterally extending centering lugs, of a valve shield comprising mating members conforming to the general outline of the flush valve and fitting about the casing thereof with their meeting portions abutting and the inner surface of the shield bearing against said lugs, the exterior surfaces of the members at said meeting portions being disposed flush with each other, and means whereby the flush valve may be secured within the shield.

2. A shield to be installed about a flush valve comprising mating members conforming to the general contour of the valve with their surfaces at the meeting portion flush with each other, the lower member of the shield having a pipe section constituting an outlet for the flush valve.

3. A shield to be fitted about a flush valve comprising upper and lower members conforming to the general contour of the valve and fitted about the same with their meeting ends abutting and their surfaces flush, means for securing the flush valve in said members, and a valve-operating member mounted upon and carried by the lower member of the shield.

4. A shield for installation about a flush valve comprising upper and lower members having their meeting ends open whereby they may be brought together to enclose the valve, means for securing the shield members to the valve, a shelf within

one member upon which the flush valve may rest, and a valve-operating element mounted upon and carried by the lower member.

5. A shield to be installed about a flush valve comprising a lower member having a body provided with an open upper end and a semi-cylindrical arm extending laterally from said upper end and having a lower portion depending from said body of pipe formation whereby to constitute an outlet from the flush valve, an upper member having a substantially cylindrical body open at its lower end to fit over the upper portion of the flush valve and provided at its lower end with a semi-cylindrical lateral arm mating with the arm on the lower shield member to fit about an inlet for the flush valve, and means for securing said shield members to the flush valve. 80

6. A shield to be installed about a flush valve comprising a lower member having a substantially cylindrical upper body portion with an open upper end and a semi-cylindrical arm extending laterally from said upper end, an internal annular shelf in the body portion of said member below said arm, a pipe section depending from said body portion to constitute an outlet for the 100 flush valve, a box formed on the outer side of the body portion of said member, an offset on the inner surface of said body portion below the shelf, a cap fitted in the outer end of said box, a valve-operating element carried by said cap and extending through the box and said offset, an upper shield member conforming to the upper portion of the flush valve and abutting the upper end of the lower shield member, and means for securing the shield members to the valve. 95
